UNITED STATES PATENT OFFICE.

JAMES R. LATHAM, OF NEW YORK, N. Y., ASSIGNOR OF ONE-HALF TO
ROBERT MILBANK, OF NEW YORK, N. Y.

NON-REFILLABLE BOTTLE.

SPECIFICATION forming part of Letters Patent No. 710,917, dated October 7, 1902.

Application filed October 30, 1901. Serial No. 80,480. (No model.)

To all whom it may concern:

Be it known that I, JAMES R. LATHAM, a citizen of the United States, and a resident of the borough of Manhattan, in the city and State 5 of New York, have invented a new and useful Non-Refillable Bottle, of which the following is a specification.

My invention relates to non-refillable bottles, and has for its object to provide improved means for automatically locking the valve thereof closed whenever the bottle is in a position to receive liquid therein.

A further object is to provide a device of the above character in which a ball is used to hold the valve closed except when the bottle 15 is inverted and a device is used for engaging the ball for locking the valve closed except when the bottle is in its inverted position.

A practical embodiment of my invention is represented in the accompanying drawings, in which—

Figure 1 is a vertical central section showing the position of the parts when the valve 25 is closed. Fig. 2 is a similar view showing the position of the parts when the bottle has been inverted or tilted into the pouring position. Fig. 3 is a vertical central section showing a modified form of device for locking the 30 valve closed, the parts being in the position which they assume when the bottle is in any other than a pouring position. Fig. 4 is a similar view showing the position of the parts when the valve is opened and the bottle is inverted into pouring position, and Fig. 5 is a 35 transverse section taken in the plane of the line A A of Fig. 3.

The neck of the bottle is herein shown as formed in two parts, the upper part or section being denoted by 1 and the lower section by 2, which lower section may be integral with the body 3 of the bottle itself. These two sections 1 and 2 may be permanently secured together in any well-known 45 and approved manner after the parts to be hereinafter described have been inserted in the neck of the bottle. In the lower section 2 there is fixed intermediate the neck-space and the interior of the body of the bottle a 50 cork 4, within which there is set a tube 5, having a flange 6, overlapping the top of the cork 4.

The cork-valve 7 is preferably of disk form, as shown, and it is intended to rest with its face pressing against the top of the tube 5 to effect a closure thereof. This cork 7 is of sufficient size to float the valve to its seat whenever the bottle shall be tilted to a position with its mouth below the horizontal plane, and water is forced into it in that position.

The disk-valve 7 is provided with a backing consisting of a thin strip or plate of metal 60 8, fastened to the cork, the opposite ends of the said plate or strip having a loose sliding engagement with the upright portions of a bail 9, the opposite ends of which are fixed in 65 the flange 6 of the tube 5. This bail 9 serves as a support for the gravity-closing device, which is constructed and arranged as follows: A pintle-pin 10 is mounted to rotate in elongated bearings in the crown of the bail and 70 supports a weighted gravity incline 11, the weight 12 of which is so arranged that the incline will be directed from a point above the center of the valve 7 obliquely toward the same except when the bottle is inverted into 75 its pouring position. This tubular incline 11 has a ball 13 therein arranged to freely roll along within the same, which ball will at all times rest against and hold the valve 7 closed except when the bottle is inverted.

In the form shown in Figs. 1 and 2 the device which I employ for locking the ball against the valve when the valve is in its closed position is constructed and arranged as follows: A rocking lever 14 is hinged intermediate its ends to a suitable lug 15 on the exterior of the incline and projects into the interior thereof, where it engages the ball 13. The exterior end of the lever 14 is provided with a swinging locking tailpiece or dog 16, 90 which is of sufficient weight to swing into engagement with a stop or abutment 17 on the exterior of the incline when the bottle is in any other than an inverted position. When the said dog 16 is engaged with the abutment 95 or stop 17, the lever 14 is locked in its position in engagement with the ball, locking the ball in its position against the closed valve 7. When the bottle is inverted, the dog 16 will swing away from its engagement with the 100 abutment 17, thus permitting the lever 14 to swing outwardly and permitting the ball 13

to roll along the incline and release the valve 7, thus permitting it to open.

In the form shown in Figs. 3, 4, 5 the ball is locked in its position, holding the valve 5 closed whenever the bottle is in any other than an inverted position by means of a sliding block 18, which is fitted to slide in a tube 19 at right angles to the tubular portion of the incline 11, within which the ball is located. A cap 20 is removably secured to the outer end of the tubular portion 19 of the incline, which cap is sufficiently heavy to keep the incline at all times in position to direct the ball 13 against the valve 7 except when 15 the bottle is inverted. When the bottle is inverted, the block 18 will slide along within the tubular portion 19 a sufficient distance to permit the ball 11 to roll toward the mouth of the bottle away from the valve, thus releasing the valve and permitting it to open 20 from for the purpose of pouring out the liquid within the bottle.

To prevent tampering with the locking device, I provide a suitable perforated guard- 25 plate 21, located between the said locking device and the mouth of the bottle, which guard-plate in the present instance is shown as being secured between the meeting edges of the inner and outer sections of the neck of the bottle.

30 What I claim is—

1. The combination with the neck of a bottle provided with a passage-way for opening

communication between the interior of the neck and the interior of the body of the bottle, of a valve for closing said passage-way, a 35 ball for holding the valve closed, a gravity-controlled incline for directing the ball into its position for holding the valve closed when the bottle is in other than an inverted position and means for automatically engaging 40 the ball for locking the valve in its closed position, substantially as set forth.

2. The combination with the neck of a bot- 45 tle provided with a passage-way for opening communication between the interior of the neck and the interior of the body of the bottle, of a valve for closing said passage-way, a gravity-controlled incline, a ball therein ar- ranged to hold the valve closed and means for automatically locking the valve in its closed 50 position comprising a rocking lever engaging the ball and a gravity-controlled tailpiece or dog arranged to engage the incline when the bottle is in certain positions for locking the lever and thereby the ball and valve against 55 movement, substantially as set forth.

In testimony that I claim the foregoing as my invention I have signed my name, in pres- ence of two witnesses, this 29th day of Octo- 50 ber, 1901.

JAMES R. LATHAM.
